UNITED STATES PATENT OFFICE.

GUY R. PRIDE, OF JACKSONVILLE, FLORIDA.

VESSEL OR CARRIER.

No. 840,957.

Specification of Letters Patent.

Patented Jan. 8, 1907.

Application filed August 11, 1906. Serial No. 330,153.

To all whom it may concern:

Be it known that I, GUY R. PRIDE, a citizen of the United States, residing at Jacksonville, in the county of Duval, State of Florida, have invented new and useful Improvements in Vessels or Carriers, of which the following is a specification.

My invention relates to vessels or carriers for treating substances to extract one or more of their component parts, and is more particularly directed to the bottoms of such vessels or carriers, wherein novel provision is made, first, for permitting the escape of material therefrom in a liquid or gaseous state, and, secondly, for facilitating the dumping of either the entire contents of said vessel or carrier or a portion of said contents, as may be desired. These objects I accomplish in the manner and by the means hereinafter described and claimed, reference being had to the accompanying drawings, in which—

Figure 1 is a bottom plan view of a vessel or carrier embodying my improved construction of bottom. Fig. 2 is a vertical sectional view of the lower portion of the vessel or carrier, taken on the line 2 2, Fig. 1. Fig. 3 is an enlarged detail sectional view of one corner of the vessel or carrier, showing the latch for retaining one side of the bottom closed. Fig. 4 is an enlarged detail sectional view taken on the line 4 4, Fig. 1. Fig. 5 is an enlarged detail plan view, partly broken away, of one of the discharge-openings in the bottom of the vessel or carrier, together with the means for protecting the same. Fig. 6 is an enlarged detail side elevation of the same, partly broken away.

Similar numerals of reference denote corresponding parts in the several views. In the said drawings the reference-numeral 1 denotes the body of the vessel or carrier, of which I have shown only the bottom edge, the construction of its upper part forming no part of the present invention. Passing centrally across the bottom of the vessel or carrier 1 is a bar 2, the same being fixed to said vessel or carrier and being provided with a series of downwardly-projecting ears 3, to which are hinged the straps 4, bolted to the under side of the two semicircular sections 5, constituting the bottom of the vessel or carrier. On opposite sides of the vessel or carrier 1 I provide latches 6, hinged to the outside of said vessel or carrier and adapted to engage under the edges of the sections 5 when the latter are in their closed position to

retain them in said position, said sections 5 being each provided with an upturned lip 7, bolted to the under sides of said sections at their outer edges and adapted to embrace 60 the lower edge of the vessel or carrier 1.

In order to provide for the complete emptying of the vessel or carrier 1 when the sections 5 are released from their latches 6 and permitted to drop, I have provided the two 65 plates 8, bolted to the angular sides of the central bar 2 and at their ends to the inner wall of the vessel or carrier, as best seen in Fig. 4, said plates coming in contact with each other at their upper edges and being 70 bolted together, the same being so shaped as to constitute an inverted V, having practically a knife-edge, whereby no obstacle will be offered to the discharge of the contents of the vessel or carrier when the bottom sections 5 are permitted to drop.

At the center of the bar 2 I have shown in Fig. 1 a construction providing for the passage of a steam-pipe through the bottom of the vessel or carrier, but the same forming no 80 part of the present invention and being specifically covered in an application filed by me of even date herewith, Serial No. 330,152, further description of the same is deemed unnecessary.

My improved means for providing for the discharge from the vessel or carrier 1 of substances in a liquid or gaseous state and yet preventing the discharge of solid substances and at the same time preventing the weight 90 of said solid substances from interfering with the liquid or gaseous discharge will now be described, as follows: Through the bottom sections 5 of the vessel or carrier I provide a series of apertures 9, and over each of said 95 apertures I locate an imperforate plate 10, said plate being of somewhat larger diameter than its underlying aperture 9 and being supported at a distance above said aperture, a series of bolts 11, each passing loosely 100 through a sleeve 12, that engages between the under side of plate 10 and the inner surface of the section 5, serving to maintain said plate firmly in its raised position. Around the exterior of the sleeves 12 I locate a foraminous screen 13, the same filling the space 105 between the plate 10 and the section 5, and as it underlies the edge of said plate 10 it is protected from the material on top of said plate. From this description it will be seen 110 that the sections 5, constituting the bottom of the vessel or carrier 1, present to material

discharged thereinto a substantially solid and imperforate surface which at the same time permits of the free egress of liquid and gaseous substances.

5. In an application filed of even date here-with, Serial No. 330,151, I have disclosed one of the uses to which my improved vessel or carrier may be put; but it will be evident that it is equally applicable to any form of 10 apparatus wherein a mass of solid material is charged and in which openings at the bottom for the passage of liquid or gaseous matter are desired. Furthermore, my im- 15 proved construction of dumping bottom sec-tions, in combination with the inverted-V- shaped central guard, is also applicable to any form of dumping apparatus, and in this connection I do not wish to limit myself to a bottom formed of two semicircular sec- 20 tions, as the number of sections may be in- creased by further subdividing said sections, if desired, or by providing a plurality of bars 2 radiating from the center, to each of which a bottom section may be hinged.

25 Having thus described my invention, what I claim as new, and desire to secure by Letters Patent, is—

1. An apparatus of the character described, embodying a vessel or carrier body, a central bar fixed in the bottom of said body, a plu- 30 rality of bottom sections hinged to said central bar, means for detachably retaining said sections closed, and an inverted-V-shaped guard on top of said central bar presenting 35 an upwardly-projecting knife-edge.

2. An apparatus of the character described, embodying a vessel or carrier body, a bot- 35 tom thereto having one or more apertures therein, imperforate plates of greater dia-

ter than said apertures located centrally 40 above said apertures, a series of sleeves sup- porting said plates at a distance above the vessel or carrier bottom, and bolts passing through said sleeves and connecting said plates with the vessel or carrier bottom. 45

3. An apparatus of the character described, embodying a vessel or carrier body, a bot- 50 tom thereto having one or more apertures therein, imperforate plates supported cen- trally above said apertures at a distance 55 above the vessel or carrier bottom and of a diameter sufficient to cover said apertures, and an annular foraminous screen located vertically in the space between each of said plates and the vessel or carrier bottom and outside of the circumference of said aper- 60 tures.

4. An apparatus of the character described, comprising a vessel or carrier body, a bot- 65 tom thereto having one or more apertures 60 therein, imperforate plates of greater dia- meter than said apertures located centrally above said apertures, a series of sleeves sup- porting said plates at a distance above the vessel or carrier bottom, bolts passing 70 through said sleeves and connecting said plates with the vessel or carrier bottom, and an annular foraminous screen located ver- 75 tically in the space between each of said plates and the vessel or carrier bottom and lying against said sleeves.

In testimony whereof I have hereunto set my hand in the presence of two subscribing witnesses.

GUY R. PRIDE.
